UNITED STATES PATENT OFFICE.

EDWIN N. PREBLE, OF BEVERLY, MASSACHUSETTS, ASSIGNOR TO UNITED SHOE MACHINERY CORPORATION, OF PATERSON, NEW JERSEY, A CORPORATION OF NEW JERSEY.

WORK-SUPPORT FOR SHOE-LEVELING MACHINES.

1,386,655.

Specification of Letters Patent.

Patented Aug. 9, 1921.

Application filed February 4, 1919. Serial No. 274,979.

To all whom it may concern:

Be it known that I, EDWIN N. PREBLE, a citizen of the United States, residing at Beverly, in the county of Essex and State of Massachusetts, have invented certain new and useful Improvements in Work-Supports for Shoe-Leveling Machines; and I do hereby declare the following to be a full, clear, and exact description of the invention, such 10 as will enable others skilled in the art to which it appertains to make and use the same.

The present invention relates to work supports for shoe leveling machines and, more 15 particularly, to metal lasts or followers employed in connection with leveling machines of the rolling pressure type and adapted to be received within a shoe to support the latter during the leveling operation.

20 Machines of the type disclosed in the patent to Mayo, No. 861,746, July 30, 1907, are provided with a metal follower for supporting the shoe and a coöperating pressing form, together with mechanism for relatively 25 rocking the pressing form and follower to traverse the pressing form over the shoe sole. This type of machine is used principally for leveling the soles of McKay shoes. It is customary to provide a cast-iron follower 30 having a slot cored out of the heel end to receive the correspondingly shaped end of a supporting post, a pin which passes through the follower and the end of the post serving to rigidly secure the follower to the post. As the follower has to withstand extremely 35 heavy pressure in this type of machine, it is necessary that the end of the post fit the slotted portion of the follower accurately, and for this reason it is customary 40 to grind the interior walls of the slot accurately to predetermined dimensions.

According to the usual practice which formerly existed, the pressing form was designed to engage with and level only the 45 forepart, and the shank of the shoe sole, but the present tendency is to level the entire sole including the heel seat. With the usual follower having a slot in the heel and extending completely from top to bottom, this 50 mode of operation mars the inside of the sole at the heel seat, and this is particularly objectionable in those McKay shoes which are made in imitation of welt shoes and are provided with an inner sock lining of soft

material, the edges of the slot in this case 55 frequently cutting the sock lining sufficiently to render it unfit for use.

One object of the present invention, then, is to provide an improved follower capable 60 of successful embodiment in existing machines of this type and constructed in such a manner that the heel seat of the shoe may be leveled without damage.

With this object in view, one feature of the invention comprises a cast metal follower 65 having a parallel sided slot formed in the heel end, the walls of which are accurately finished to predetermined dimensions, and a metal plate supported upon a ledge formed in the face of the follower to close the top 70 of the slot and afford a smooth bearing for the shoe bottom at the heel seat.

Still further features of the invention consist in certain novel features of construction, combinations and arrangements of parts 75 hereinafter described and claimed the advantages of which will be obvious to those skilled in the art from the following description.

In the accompanying drawings illustrating 80 the preferred form of the invention, Figure 1 represents a side elevation of the improved work support; Fig. 2 is an end elevation of the work support; Fig. 3 is a top plan view of the follower before its application to the supporting post; Fig. 4 is a side elevation of the follower with the heel 85 end broken away and shown in section; and Fig. 5 is a detail illustrating the heel end 90 of the follower before the plate is applied to close the slot.

As shown in the drawings, the follower indicated at 10 is shaped to fit approximately within the interior of the shoe and is provided with a slot 11 at the heel end which 95 receives the upper end 12 of the usual supporting post 14. The inner end of the slot is inclined as shown in 15 and is adapted to bear upon a correspondingly inclined face 16 of the post, the last being secured to the 100 upper end of the post by a pin 17 passing through the sides of the last and the post as indicated in Figs. 1 and 2. This construction is intended to afford a rigid connection between the follower and the supporting 105 post and to permit the follower to withstand the comparatively heavy leveling pressure without breaking. The follower is inva-

riably made of cast-iron with the slot 11 cored out during the casting operation, after which the slot is accurately ground to predetermined dimensions in order that it may 5 fit the end of the post 14 without any slack. When the slot extends completely through the follower from top to bottom, it is a comparatively simple matter to grind the interior with a wheel which is the same width 10 as the width of the finished slot, but when it is desired to close the top of the slot a difficult problem is presented for if the slot is initially cored out with a closed top, it is practically impossible, from a manufacturing 15 standpoint, to perform the requisite finishing operation upon the interior.

According to the present invention, the cast-iron follower is provided with a slot cored in the heel end and extending from 20 top to bottom of the follower. The walls of this slot are then ground in the usual manner to predetermined dimensions to form a parallel sided slot which shall fit the upper end of the supporting post closely. When this 25 operation has been completed, a recess 18 is milled in the face of the follower surrounding the upper edges of the slot to form a supporting ledge for a metal plate 20 which closes the top of the slot and affords 30 a smooth bearing for the shoe at the heel seat. As will be evident from an inspection 35 of the drawings, the upper surface of the plate is shaped to conform with the curvature of the face of the follower. The plate is permanently secured to the follower by a dowel pin 21 passing through the edge of the plate and the follower, as indicated in Fig. 4.

A work support constructed in this manner has certain manifest advantages as it 40 may be manufactured economically, is capable of withstanding the heavy leveling pressures employed without breaking at the connection between the follower and the 45 post, and enables all types of shoes to be leveled at the heel seat without marring the inner portion of the shoe. It may be pointed out in connection with the breaking of the work support under the heavy pressure em-

ployed, that unless the slot in the heel end 50 of the follower fits the upper end of the supporting post accurately and without any lost motion, the follower is certain to break down at the heel portion after a very short 55 period of use.

While it is preferred to employ the specific construction and arrangement of parts shown and described, it will be understood that this construction and arrangement is not essential except as far as specified in the 60 claims, and may be changed or modified without departing from the broader features of the invention.

What is claimed is:—

1. A work support for shoe leveling machines comprising a cast metal follower having a parallel sided slot formed in the heel end, a supporting post having a correspondingly shaped end received and fitting closely within the slot, a pin passing through the 70 post and sides of the follower, and a metal plate supported upon a ledge formed in the face of the follower to close the top of the slot and afford a smooth bearing for the shoe bottom at the heel seat. 75

2. A work support for shoe leveling machines comprising a cast metal follower having a parallel sided slot in the heel end and a recess formed in the face of the follower 80 extending about the upper edges of the slot, and a metal plate supported upon the ledge formed by the recess and having an upper surface flush with the face of the follower to afford a smooth bearing for the shoe bottom at the heel seat. 85

3. A work support for shoe leveling machines comprising a cast metal follower having a parallel sided slot formed in the heel end, a supporting post having a correspondingly shaped end received and fitting closely 90 within the slot, means for securing the follower upon the post, and a metal plate closing the top of the slot and having an upper surface flush with the surface of the follower to afford a smooth bearing for the 95 shoe bottom at the heel seat.

EDWIN N. PREBLE.
